(74) Attorney, Agent, or Firm — Legalforce RAPC Worldwide(57) **CLAIM**

The ornamental design for a neck massage device, as shown and described.

DESCRIPTION

FIG. 1 is a front-side perspective view of a neck massage device, showing my new design;

FIG. 2 is a back left-side perspective view thereof;

FIG. 3 is a front right-side isometric view thereof;

FIG. 4 is a bottom right-side view thereof;

FIG. 5 is a top left-side view thereof;

FIG. 6 is a front elevational view thereof;

FIG. 7 is a left elevational view thereof;

FIG. 8 is a right elevational view thereof;

FIG. 9 is a top plan elevational view thereof;

FIG. 10 is a bottom plan elevational view thereof;

FIG. 11 is a right-side view thereof;

FIG. 12 is another right-side view thereof; and,

FIG. 13 is another right-side view thereof.

The broken lines on the surface portions indicate the pattern of the neck massage device.
